CLAIM

The ornamental design for the floor mat, as shown and described.

DESCRIPTION

FIG. 1 is a perspective view of the floor mat of the present invention;

FIG. 2 is top plan of the floor mat of FIG. 1; and,

FIG. 3 is an enlarged view of a portion of FIG. 2.

The broken line showing of the lines on the floor mat is included for the purpose of illustrating environment and forms no part of the claimed design.

1 Claim, 2 Drawing Sheets

FIG. 2
